Attorneys

UNITED STATES PATENT OFFICE.

BENJAMIN GILOWITZ, OF NEW YORK, N. Y., ASSIGNOR OF ONE-HALF TO HARRY ARONSTAM, OF BRONX, NEW YORK, N. Y.

HEEL-LIFT-ATTACHING MEANS.

Application filed November 9, 1925. Serial No. 67,904.

The invention relates to means for attaching heel lifts whether formed of leather, rubber or other materials, and the present disclosure is related primarily to ladies' 5 shoes having wooden heels.

It is the object of the invention to provide a heel lift having an improved reinforcing means and means for covering said reinforcing means from view.

10 With the foregoing in view, the invention resides in the novel subject matter herein-after described and claimed, the description being supplemented by the accompanying drawing.

15 Figure 1 is a sectional view of a heel and lift showing the application of the invention.

Figures 2 and 3 are perspective views of certain elements shown in Fig. 1.

My improved reinforcing means and cov- 20 ering therefor consists of a metal plate 16° applied to the upper side of the lift L and provided with an upstanding flange 22° to engage the front side of the heel H. A sheet 33 of leather or other desired material is 25 connected with the front edge portion of the lift L to extend upwardly in front of the flange 22°, so as to obscure the latter from view, said sheet being adapted to be secured against the front side of the heel H. The 30 lower edge of the sheet 33 is turned inwardly and securely clamped between the top of the front edge of the lift and the attaching plate or between the top of the lift and the bottom of the heel. The plate 16° is prefer- 35 ably provided with downwardly projecting prongs 34 which may be stamped therefrom. These prongs are intended to penetrate the lift L for securing the plate and lift together, but if desired other connecting means 40 could be provided between said plate and lift.

The invention is simple and inexpensive, may be easily manufactured, and is very desirable. However, within the scope of the

invention as claimed, modifications may be 45 made.

I claim:—

1. A heel lift having a rigidly attached reinforcing plate whose front end is extended upwardly to provide a flange adapted to 50 contact with the front side of a shoe heel, and a sheet of flexible material secured to the lift and extending upwardly therefrom in front of said flange, said sheet being adapted to be secured to the front side of 55 the heel, the lift and plate being formed with openings to receive an attaching fastener.

2. A heel lift having rigidly attached to its upper side a reinforcing plate, said plate 60 having substantially the same size and shape as the upper side of the lift, a relatively small upwardly turned flange on the front end of said plate for engagement with the front side of a shoe heel, and a sheet of flex- 65 ible material having an inwardly turned lower edge secured between the flanged edge of said plate and the adjacent surface of the lift, said sheet extending upwardly in front of said flange and being adapted to be se- 70 cured to the front side of the heel, the lift and plate being formed with openings to receive an attaching fastener.

3. A heel lift having secured to the upper side thereof near its front end an upwardly 75 extending sheet of flexible material adapted to be secured to the front side of the heel.

4. A heel lift, an attaching plate secured thereto, an upwardly extending sheet of flex- 80 ible material having its lower edge turned inwardly and securely clamped between the top of the front edge of the lift and said at- taching plate, said sheet being adapted to be secured to the front side of the heel.

In testimony whereof I have hereunto af- 85 fixed my signature.

BENJAMIN GILOWITZ.
